(57) **CLAIM**

The ornamental design for a wireless fob duplication device,
as shown and described.

DESCRIPTION

FIG. 1 is a front, top, right perspective view of a wireless fob
duplication device showing the new design;

FIG. 2 is a left, bottom, rear perspective view thereof;

FIG. 3 is front elevation view thereof;

FIG. 4 is a rear elevation view thereof;

FIG. 5 is a left-side elevation view thereof;

FIG. 6 is a right-side elevation view thereof;

FIG. 7 is a top plan view thereof; and,

FIG. 8 is a bottom plan view thereof.

The broken lines of even length shown in the drawings
illustrate portions of the wireless fob duplication device that
form no part of the claimed design.
